(57) **CLAIM**

The ornamental design for a force arm cutting and prying blade, as shown.

DESCRIPTION

This invention was made with government support under contract. The government has certain rights in the invention. FIG. 1 is a perspective view of a force arm blade for exemplary use with a portable rescue tool;

FIG. 2 is a front elevational view of the force arm shown in FIG. 1;

FIG. 3 is a rear elevational view of the force arm shown in FIG. 1;

FIG. 4 is a top view of the force arm shown in FIG. 2;

FIG. 5 is a bottom view of the force arm shown in FIG. 2;

FIG. 6 is a left end view of the force arm shown in FIG. 2; and, FIG. 7 is a right end view of the force arm shown in FIG. 2.
